LOUNGE CHAIR

Joseph F. Laskowitz, St. Louis, Mo.

Application December 3, 1949, Serial No. 6,403

Term of patent 14 years

(Cl. D15—11)

To all whom it may concern:

Be it known that I, Joseph F. Laskowitz, a citizen of the United States, residing in the city of St. Louis and State of Missouri, have invented a new, original, and ornamental Design for a Lounge Chair, of which the following is a specification, reference being had to the accompanying drawing, forming a part thereof.

In the drawing:

Fig. 1 is a top or plan view;

Fig. 2 is a side perspective view;

Fig. 3 is a rear end elevational view, and

Fig. 4 a front end elevational view, each view showing a lounge chair of my new design.

I claim:

The ornamental design for a lounge chair, substantially as shown.

JOSEPH F. LASKOWITZ.
